UNITED STATES PATENT OFFICE.

HERBERT W. WALDMANN, OF CONCORD, WISCONSIN.

CULTIVATOR ATTACHMENT.

Application filed October 16, 1926. Serial No. 142,054.

This invention relates to cultivator attachments and it is an object of the invention to provide an attachment of this kind adapted to be arranged at the rear of a cultivator and which operates effectively to destroy weeds and to remove clods or the like.

It is also an object of the invention to provide an attachment of this kind which operates effectively to uncover corn or the like and in a manner resulting in a material saving of plants.

The invention consists in the details of construction and in the combination and arrangement of the several parts of my improved cultivator attachment whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in perspective illustrating an attachment constructed in accordance with an embodiment of my invention in applied position;

Figure 2 is a view in rear elevation of the device as herein disclosed;

Figure 3 is a view in top plan of the device as illustrated in Figure 1;

Figure 4 is a view in end elevation of the device as herein embodied;

Figure 5 is a view in perspective of the attachment unapplied.

My improved attachment as herein disclosed comprises an elongated board or head member 1 of a length to extend substantially between the rear extremities of the beams B of a cultivator. This board or member 1 at its opposite end portions has secured thereto the rods 2 and 3. The outer portions of these rods 2 and 3 each terminate in a depending extension 4 provided with an eye 5 affording means whereby the rod may be readily and effectively engaged with a beam B and more particularly by a bolt connecting preferably the second shovel of such beam.

It is to be noted that the rods 2 and 3 are of differing lengths. This is done in order to have the board or head member 1 disposed

in a slanting direction when in applied or working position.

A frame F is disposed over the outer or rear face of the board or head member 1 and extends a material distance therealong. The end members 6 of the frame F are provided with the longitudinally disposed slots 7 through which are directed the bolts 8 also disposed through the board or head member 1. Threaded upon each of the bolts 8 and 65 coating with an end member 6 is a wing nut 9 whereby the frame F is effectively held in applied position with respect to the board or head member 1. The slots 7 provide means whereby the frame F may be vertically adjusted as the requirements of practice may necessitate or prefer.

Secured to the upper member 10 of the frame F at equidistantly spaced points therealong are the upper extremities of the 75 ground engaging fingers or rods 11. These rods are of desired length and are disposed through the openings 12 provided in the lower member 14 of the frame, thus assuring the fingers or rods 11 being effectively maintained in applied position. The lower extremities of the rods or fingers 11 are disposed on a forward incline, as indicated at 15.

With my improved attachment applied to 85 a cultivator as the same passes along the plant rows, the fingers or rods 11 operate effectively to remove or destroy weeds or the like and also collect clods which may be in the soil and throw the same to one side. 90 This latter function is facilitated by the angle of slant the attachment may be applied with respect to the direction of travel of the cultivator.

From the foregoing description it is 95 thought to be obvious that a cultivator attachment constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as 100 limiting myself to the precise arrangement and formation of the several parts herein shown in carrying out my invention in practice except as hereinafter claimed.

I claim:—

1. A cultivator attachment comprising a head member, arms connected with the head member and adapted to be attached to the beams of the cultivator, bolts carried by the head member and having end portions disposed beyond the side thereof, link members having slots which receive the bolts, nuts screwed upon the bolts and adapted to clamp the link members against the head member, upper and lower cross bars pivoted to the ends of the link members and bridging the space between them, the lower cross bar having an intermediate portion disposed in a plane at a right angle to the plane in which the intermediate portion of the upper cross bar lies, and teeth pivoted to the upper cross bar and loosely received in the intermediate portion of the lower cross bar.
